UNITED STATES PATENT OFFICE.

ANTHONY ROELOFS, OF PHILADELPHIA, PENNSYLVANIA.

CAR-DOOR RETAINER.

SPECIFICATION forming part of Letters Patent No. 329,340, dated October 27, 1885.

Application filed July 9, 1885. Serial No. 171,039. (Model.)

To all whom it may concern:

Be it known that I, ANTHONY ROELOFS, a citizen of the United States, and a resident of Philadelphia, Pennsylvania, have invented 5 certain Improvements in Car-Door Retainers, of which the following is a specification.

One feature of my invention is a simple form of retainer, whereby the accidental opening of the car-door or the ready opening of the same 10 by unauthorized persons may be prevented, another feature being the combination, with said retainer, of a locking-bolt, whereby the movement of the retainer, so as to release the door, is rendered impossible without previous 15 retraction of the bolt.

In the accompanying drawings, Figure 1 is a sectional perspective view showing part of the car-door and car side with my improved retainer; Fig. 2, a similar view showing the 20 retainer combined with a locking-bolt; Figs. 3, 4, and 5, perspective views of the various parts of the retainer shown in Fig. 1; Fig. 6, a sectional plan view, on a larger scale, of the device shown in Fig. 2; Fig. 7, a front view, on a 25 reduced scale, showing the retainer combined with a seal; Fig. 8, a similar view showing the retainer and locking-bolt combined with a seal; Figs. 9 and 10, front views, partly in section, showing the locking-bolt and its tumblers, Fig. 9 showing the tumblers in position 30 to lock the bolt in its forward position, and Fig. 10 showing the tumblers adjusted to retain the bolt in the retracted position.

Although my invention comprises means 35 for locking the door in position, the main feature of my invention consists of a device intended not for locking but for retaining the door in its closed position and preventing accidental displacement of the door or ready 40 opening of the same by unauthorized persons, the device being intended as a substitute for the usual cleat nailed against the car side adjacent to the end of the door, the objection to these cleats being their insecurity and the 45 rapid destruction of the planking or sheathing of the car by the continued nailing of the cleats thereupon.

My improved retainer consists of a screw-stem, A, which, as shown, has a square head, 50 a, although a head of other polygonal shape, or one with notches or a slot or recess for the reception of a suitable operating-tool, may be

used. This screw-stem is adapted to a nut, B, forming part of a frame, D, which is secured to the end of the car-door, and preferably projects somewhat beyond the end of the strip x of the door-frame, so that the latter will not be unduly weakened by being cut away for the reception of the nut. When the door has been closed and the stem has been screwed 60 into the nut, the inner end of said stem, which, as will be seen in Figs. 5 and 6, is reduced in diameter as compared with the threaded portion, projects beyond the inner face of the door, and the head a of the stem 65 bears against the outer face of the nut. This projecting end of the stem may be received into an opening or recess in the side of the car; but I prefer to provide for its reception a socket, F, carried by the planking or sheathing of the side of the car, this socket preferably forming part of a plate, b, secured to the inner side of said sheathing, as shown in Fig. 6. The car-door is thus retained in position until the stem A has been unscrewed so as to withdraw the projecting end of the same from the socket F, and by using a suitable wrench in 70 screwing up the stem in the first instance the friction between the threads of the nut and stem, and between the face of the nut and the head of the stem, is such that the unscrewing of the same without the use of a suitable implement may be rendered impracticable, so that the entering of the car by tramps or yard 75 thieves for the purpose of pilfering is prevented. The withdrawal of the bolt from the head of the stem, is such that the unscrewing of the same without the use of a suitable implement may be rendered impracticable, so that the entering of the car by tramps or yard 80 thieves for the purpose of pilfering is prevented. The withdrawal of the bolt from the head of the stem, is such that the unscrewing of the same without the use of a suitable implement may be rendered impracticable, so that the entering of the car by tramps or yard 85 thieves for the purpose of pilfering is prevented. The withdrawal of the bolt from the head of the stem, is such that the unscrewing of the same without the use of a suitable implement may be rendered impracticable, so that the entering of the car by tramps or yard 90 thieves for the purpose of pilfering is prevented. The withdrawal of the bolt from the head of the stem, is such that the unscrewing of the same without the use of a suitable implement may be rendered impracticable, so that the entering of the car by tramps or yard 95 thieves for the purpose of pilfering is prevented. The withdrawal of the bolt from the head of the stem, is such that the unscrewing of the same without the use of a suitable implement may be rendered impracticable, so that the entering of the car by tramps or yard 100 thieves for the purpose of pilfering is prevented.

The device above described may be used alone, when it is simply desired to retain the door in the closed position, the device being much preferable to the usual cleat as regards security and durability, and being also available for retaining the door in the opened position, a supplementary socket being secured to the car-side for the reception of the end of the stem in the latter case. When it is desired to seal the stem, the wire may be passed through a lug, d, on the frame D, and through openings d' in the head of the stem, the ends of the wire being secured by the lead seal e, as shown in Fig. 7. For locking the stem, however, I prefer to combine with the same a sliding

bolt, G, as shown in Figs. 2, 6, 9, and 10, this bolt being adapted to suitable guides on the frame D, so that when its front end bears against or engages with the head of the stem A the turning of the latter is prevented unless the bolt is first retracted.

In using a seal with the bolt the wire may be passed through a lug, d, on said bolt, and through the openings d' in the head a of the stem A, as shown in Fig. 8, the ends of the wire being secured by the seal, as before; but when a key-lock is desired I make the bolt G hollow and provide the same with a series of tumblers, g, which have bits i to engage with a stump, m, projecting from the frame D. These tumblers consist preferably of simple bars of metal separated by washer-plates h, and resting upon a transverse partition, n, in the bolt, an opening being formed in the under side of the latter for the insertion of a suitable key, y, for operating the tumblers. When the bolt G is moved forward so as to engage with the head a of the retaining-stem, the bits i of the tumblers engage with the front side of the stump m and prevent the retraction of the bolt, and when said bolt has been retracted by the key the bits engage with the rear side of the stump and lock the bolt in its retracted position, so as to prevent the accidental forward movement of the bolt and the locking of the retainer thereby. The removal of the bolt G from its guides is prevented by a stud, p, the inner end of which is adapted to a threaded opening in the frame D, and is locked thereto in any suitable manner to prevent it from being unscrewed.

A lock of this character is extremely cheap and simple in construction, being composed of plain bars or plates of metal without springs, and requiring no costly finishing or fitting, the working parts being entirely within the bolt, and the key-hole being on the under side of the latter, so that the lock is not likely to become clogged with snow, ice, or dirt.

In order to prevent ready access to the tumblers for the purpose of picking the lock, I form the key-hole in the under part of the bolt at a point more or less remote from that at which the tumblers are exposed to the action of the key, a longitudinal movement of the latter being necessary after it has been insert-

ed in the key-hole before it is in position to act on the tumblers, the shank of the key traversing a slot, s, formed in the bottom of the bolt and communicating with the key-hole t. The opening in the socket F is larger than the inner end of the stem A both vertically and horizontally, so that the sagging of the car will not prevent the entrance of the stem into the socket; nor will extreme accuracy in the adjustment of the door be required.

I claim as my invention—

1. A car-door retainer in which are combined a nut secured to the door, a screw-stem adapted to said nut, and having a head bearing up on the face of the same when the stem is screwed in, and a car-side having an opening or recess for the reception of the inner projecting end of the stem, all substantially as specified. 65

2. The combination of the car-door having a nut, and a screw-stem adapted to said nut, with a car-side having an opening or recess larger than the end of said stem to receive the same, and a bolt for locking the screw-stem, substantially as specified. 70

75 3. The combination of the car-door, and the screw-stem forming a retainer therefor, with the locking-bolt guided on the car-door, and carrying a series of tumblers adapted to engage with a fixed stump on the door, as specified. 80

4. The combination of the car-door, and the screw-stem forming a retainer therefor, with the locking-bolt guided on the door containing a series of tumblers, and having a key-hole 85 in the under side, as specified.

5. The combination of the car-door, and the screw-stem forming a retainer therefor, with the locking-bolt guided on the door, and containing a series of tumblers, said bolt having 90 in the under side a key-hole, and a longitudinal slot communicating therewith, so as to permit longitudinal movement of the key after its insertion, as specified.

In testimony whereof I have signed my name 95 to this specification in the presence of two subscribing witnesses.

ANTHONY ROELOFS.
